UNITED STATES PATENT OFFICE.

WILLIAM A. BAKER AND FREDERICK A. RAMLER, OF TOLEDO, OHIO.

SMOKE CONSUMER.

Application filed May 27, 1919. Serial No. 300,126.

To all whom it may concern:

Be it known that we, WILLIAM A. BAKER and FREDERICK A. RAMLER, citizens of the United States of America, residing at Toledo, Lucas County, Ohio, have invented a new and useful Smoke Consumer; of which the following is a specification.

This invention relates to fuel burning apparatus.

10 This invention has utility when incorporated in furnaces, especially of the hard fuel type for heating buildings.

Referring to the drawings:

Fig. 1 is a perspective view, with parts 15 broken away, of a hot air furnace having an embodiment of the invention incorporated therewith;

Fig. 2 is a section on the line II—II, Fig. 1,

20 Fig. 3 is a section on the line III—III, Fig. 1,

Fig. 4 is a section on the line IV—IV, Fig. 3.

25 Fig. 5 is a vertical longitudinal section of the furnace of Fig. 1; and Fig. 6 is a transverse section thereof on the line VI—VI, Fig. 5.

The furnace is provided with the front 1 having hard fuel supply or fire door 2, and 30 therebelow an ash door 3. Extending rearwardly from this furnace front 1 is the furnace housing 4. The three forward sections of this housing 4 are shown as including grates 5 over the ash chamber 6. Accordingly, in the use of this furnace with coal, 35 this section over the grates 5 is the main firing or fueling chamber. There is shown a horizontal extension rearwardly therebeyond providing a draft way or combustion chamber 7, from which the products of combustion may pass to the heating passages 8, over the furnace housing proper, on their 40 way to the stack by flue 9'.

An upstanding section 9 having three inwardly projecting lugs 10 from the inner convex faces of its corrugations 11 is shown 45 in position as the second section from the front of the furnace housing 4, while on the opposite side of the housing such a lug 50 carrying section 9 is the third section. Openings 12, 13, from the inside of the furnace housing are disposed in the sections 9 below the lugs 10.

As thus interchangeably equipped for 55 general installation or special substitution

in existing furnaces, section 9 may carry the air supply device of smoke consuming utility in accordance with the invention herein. This device includes a box or chamber member 14 having along the upper side thereof three eyes 15 through which the lugs 10 may extend for suspending the member 14 inside of the furnace above the grates 5 adjacent the combustion chamber 7. Extending through the openings 12, 13 of the section 9, 60 and integral with the cast iron member 14, are supply duct sections or necks 16, 17, having vertical side grooves 18, which when in position as assembled with the section 9, 65 oppose grooves 19 vertically extending in the section 9. Accordingly a dropping of pins 20 into the grooves 18, 19, serves to lock the member 14 into assembled suspended position in the furnace. Upper section 21, assembled with lower duct section 70 22 by bolts 23 have flange extensions 24 embracing the outward extensions or collars of the openings 12, 13, carrying the neck duct sections 16, 17, and retain the pins 20 in position, while assembly of the sectional 75 L-supply duct 21, 22, is maintained by bolts 25 engaging ribs 26 of the section 9. Duct sections 27, 28, are assembled by bolts 23 and connected by bolts 29 through flanges 30 of adjacent housing sections to provide a continuous cast iron high-temperature-resisting, 80 air-leakage-preventing duct to the furnace front 1. At the furnace front 1, adjustable damper means 31 may be shifted to control the air supply rate to the member 14. This 85 air supply through the duct along the outside of the furnace housing may be warmed, but upon entering the member 14, it becomes more highly heated in the elongated chamber 32 thereof. From this chamber 32, 90 this hot air may pass inward and upwardly out the series of openings 33. It may be dispersed downwardly and inwardly through series of openings 34, 35.

This controllable dispersion of highly 100 heated air adjacent the rearward region of the fuel receiving chamber of the furnace is effective in providing oxygen for completing combustion in the combustion chamber. This utilizes the full heating energy of the 105 fuel in the most desirable region of the furnace, distributes such heat action throughout the furnace, thus avoiding with the same capacity, excessive local heating for deleterious action say in the fueling chamber. The 110

air supply is so dispersed as to be thorough in completing combustion and may be controlled for accurately determining complete combustion. There is no chilling of the forward portion of the firing chamber by excessive supply of cold air in such region. By actual test applicants have brought about advantages of considerable percentage utility by delivering this heated air supply in this after location, even over a forward heated air supply.

When this device is applied to a bituminous coal heating furnace, it is desirable when one device is applied to the region of the third section on one side, that the device be applied say to the second section on the other. As so arranged there may be a reduction in chimney or stack draft in the use of the device herein with increase in the useful heat developed. For instance, a furnace without this device operated to give 1900° F. in the region 7 had a considerable draft, and the temperature of the stack gases were approximately 700° F. With like fuel this same furnace with less draft produced 2500° F. in the region 7 and the temperature of the stack gases here was kept down to approximately 700° F. as before.

What is claimed and it is desired to secure by Letters Patent is:

1. A furnace embodying a housing provided with a combustion chamber, there being a pair of openings into the furnace at said chamber and lugs projecting into the chamber from the housing adjacent said openings, of an auxiliary air supply device comprising an elongated chamber having air supply extensions protruding through said openings, eyes for engaging the lugs in sustaining the chamber of the device in the combustion chamber, and series of outlet holes variously directed from the device chamber into the combustion chamber.

2. In a furnace having a combustion chamber having walls, a pair of opposing heated air delivery means for the chamber including air supply chambers and lugs for hanging the air supply chambers in the combustion chamber said air chambers being provided with air supply duct extensions through said walls independently of the lugs, said extensions anchoring the supply chambers in position in the furnace in addition to the hanging of said chambers, and a row of downwardly directed air outlets

from the supply chambers into the combustion chamber.

3. A furnace having a main combustion chamber and an extension therebeyond, and an air supply device comprising a housing having a chamber with a plurality of outlets therefrom for dispersing air heated in the device chamber beyond the main combustion chamber, said device chamber having a supply opening duct and mounting means in addition to the supply opening duct and wholly interior of the furnace for suspending the device in heat receiving position in a furnace.

4. A furnace having a front, a furnace housing connected to the front and extending rearwardly therefrom, grates in said housing extending short of the rearward extent of the housing, a duct extending along the housing from the furnace front and outside the furnace to provide an air heating supply passage, a device sustained on the inside of the furnace housing above the grates and restricted to the region adjacent the extension therebeyond, said device comprising a chamber in communication with said duct and having variously directed outlet openings for dispersing heated air into the furnace rearward of the grates, and lugs within the furnace for sustaining said device.

5. A furnace having a housing provided with grates and an extension rearward from the grates, said housing having an upstanding section adjacent the rearward portion of the grates provided with lugs projecting into the furnace and openings through said housing into the furnace spaced from the lugs, and an air supply device comprising a chamber independently of said housing hung on the lugs, said chamber having openings for delivering air into the furnace, said chamber in addition to hanging on the lugs also having supply duct sections protruding into the furnace from through said housing openings upward from the region of the grates and adjacent said lugs, means coacting with the duct sections for maintaining the chamber as hanging on the lugs in position, and means for varying the air supply to the chamber.

In witness whereof we affix our signatures.

WILLIAM A. BAKER.
FREDERICK A. RAMLER.
